UNITED STATES PATENT OFFICE.

BAPTISTE YCRE, OF NEW YORK, N. Y.

BAKER'S OVEN.

SPECIFICATION forming part of Letters Patent No. 762,461, dated June 14, 1904.

Application filed October 10, 1903. Serial No. 176,519. (No model.)

To all whom it may concern:

Be it known that I, BAPTISTE YCRE, a citizen of the Republic of France, residing in New York, borough of Manhattan, and State of New York, have invented certain new and useful Improvements in Bakers' Ovens, of which the following is a specification.

This invention relates to certain improvements in bakers' ovens by which charging and

removing of the articles to be baked is greatly facilitated, as two men can work at the same time on the oven, and by which a quicker and better baking of the article is obtained and the sole-space considerably increased as compared with the sole-space of the ovens heretofore in use; and for this purpose the invention consists of improvements in bakers' ovens, which will be fully described hereinafter and finally pointed out in the claims.

In the accompanying drawings, Figure 1 is a front elevation of my improved baker's oven. Fig. 2 is a front elevation of the upper part of the oven, showing the gate and some of the closing-blocks and gate in open position. Fig. 3 is a vertical transverse section on line 3 3, Fig. 2, drawn on a larger scale. Fig. 4 is a vertical longitudinal section of my improved baker's oven on line 4 4, Fig. 1. Fig. 5 is a detail plan view of one of the baking-shelves. Fig. 6 is a vertical transverse section on line 6 6 of Fig. 5. Fig. 7 is a horizontal section on line 7 7, Fig. 4; and Figs. 8 and 9 are respectively a detail top view and a side view of the toothed lever for adjusting the closing-blocks of the baker's oven.

Similar letters of reference indicate corresponding parts.

Referring to the drawings, A represents the baking-chamber of my improved baker's oven, which is preferably of cylindrical shape—that is to say, circular in cross-section in the direction of the vertical center plane of the chamber. The walls of the baking-chamber are made of brickwork in the usual manner. The baking-chamber is provided with the usual bottom, side, rear, and top flues f, through which the products of combustion are passed from the fireplaces F of the oven to the chimney, so as to heat up the walls and the interior of the baking-chamber. The products of com-

bustion are drawn from the fireplaces through the side and bottom flues to the rear flues, then in upward direction to the top flues, and out in the chimney, the flue connections being arranged in any approved manner, provided that a thorough distribution of the products of combustion around the walls of the baking-chamber and a uniform heating of the same is obtained. Through the center of the baking-chamber extends a shaft S, which is supported in suitable journal-bearings S' in the side walls A' of the baking-chamber A. On the shaft S are supported at the interior of the baking-chamber A two spider-frames B, consisting of six radial arms b, that are connected at their outer ends by a ring-shaped brace-frame b', as shown in Fig. 4. The spider-frames B are provided with transverse studs b³, each of which acts as a shaft or support for a shelf D, provided at each side with hangers h, attached to the frame of the shelf, and with perforations or bearings h', engaged by the studs b³ of the spider-frames B. The shelves D are made of suitable metal and provided with openings d and grooves d², surrounding said openings, and tiles d', covering said openings and fitting in said grooves of the shelves, so as to be on a level with the shelves. The shelves D are made of equal length, but alternately of larger and smaller width, so as to enlarge the area and permit the unobstructed turning of the supporting spider-frames B without one shelf interfering with the other during the turning motion of the frames. For this purpose the studs b³ are so arranged on the spider-frames that the wider shelves supported thereby are pivoted nearer to the center of the frames than the narrower shelves. The shaft S is extended through one of the side walls A' of the oven to the outside and is provided with a sprocket-wheel w, to which intermittent rotary motion is imparted by a sprocket-chain w' and a second sprocket-wheel w² on a second shorter or stud-shaft w³, to the end of which a large hand-wheel H is applied, so as to permit the turning of the frames B and shelves D by the attendant from the outside of the oven.

In the front wall of the oven is arranged a main opening O, which extends across the entire width of the oven and which is closed by

means of an exterior drop-gate E, which is suspended from a suitable chain g and balanced by a counterweight g' , so as to be easily opened and closed. The drop-gate E is guided 5 in suitable ways e , formed by upright side rails e' , which are attached to the front wall of the oven at each end of the front opening O of the baking-chamber, as shown in Figs. 1 and 2. Immediately adjacent and back of 10 the drop-gate E is arranged a second gate E', adapted to be raised or lowered by a suitable chain g^2 and weight g^3 . The second gate E' consists of a frame E², which is provided near its bottom with guideways E³ and near its ends 15 with two sets of parallel guideways E⁴. In these guideways E⁴ are auxiliary gates E⁵, which are likewise balanced by chains g^4 , passing over suitable pulleys and counterweights g^5 , so as to be closed or opened independently 20 of the second gate E' for giving access to the ends of the baking-chamber. Between the auxiliary gates E⁵ a number of closing-blocks E⁶ are arranged adapted to be moved in the guideways E³ of the frame E², four being 25 shown in the drawings. The blocks are made of wrought-iron or other suitable material, which may or may not be lined with refractory material, and are provided at their lower ends with teeth t and slots t' . The frame E², 30 together with the closing-blocks E⁶ and auxiliary gates E⁵, can be raised when the entire main opening of the baking-chamber is to be opened for charging or discharging the articles from the shelves.

35 The front charging-board of the oven is provided with holes m , in which the pin l of a lever L, which is provided with a toothed segment L', is inserted. The toothed segment is adapted to engage with the slots t' of the 40 closing-blocks, so that on moving the lever the blocks may be moved. The space for shifting the blocks E⁶ to the left or right is obtained by raising the auxiliary gates E⁵, the space obtained being then utilized by 45 shifting the closing-blocks E⁶ into the same. By these means access may be had to any part of the baking-chamber, either at the ends by simply raising one of the auxiliary gates E⁵ or in the central part of the oven 50 by raising any of the auxiliary gates E⁵ and sliding the blocks E⁶ by the toothed segment so as to permit access to the interior of the oven. So, for instance, when it is desired to charge the baking-chamber the auxiliary gates E⁵ are opened and the shelves charged 55 through the openings formed thereby. Then the closing-blocks E⁶ are shifted laterally into the opening formed by the raising of the auxiliary gates E⁵, so as to form an opening adjacent thereto corresponding to the size of 60 the shifted block, through which the next section of the shelf is to be charged, and so on until the entire shelf is charged. When the middle blocks are shifted, a large middle 65 opening is obtained, through which the mid-

dle section of the shelf is charged. After the charging of the shelves is accomplished the blocks are returned into their normal position, as shown in Fig. 1, after which the hand-wheel is operated so as to bring the next 70 shelf on a level with the bottom of the main opening, after which the operation is repeated for charging the shelves, and so on until all the shelves are charged. As one shelf after the other is charged the next preceding charged shelf is lifted into the upper part of the baking-chamber, and thereby subjected to an atmosphere having a higher temperature than that to which the first was subjected during the charging of the same. Consequently the other articles being transferred directly into an atmosphere of higher temperature will be quickly raised, so as to make them lighter and assume a fuller and larger size. From the upper hotter part of the baking-chamber the articles to be baked gradually pass into the lower part of the baking-chamber, where there is a lower temperature and where the baking is completed. In this manner the same effect is obtained which has 90 been heretofore obtained by means of two ovens, one of which is very hot and from which the articles were transferred into an oven having a lower temperature in which the baking operation was completed. 95

My improved baking-chamber, with rotary shelves, combines the advantages of the two baking-ovens of different temperatures heretofore in use. The baking-oven is provided with the usual accessories, such as dampers n 100 for the different flues, cleaning-flues, peep-openings n' for observing the progress of the baking operation, &c. By the dampers n and heating-flues f the temperature of any part of the oven can be readily controlled and 105 adapted for the special articles to be baked. The flues are so arranged that they can be readily cleaned of soot and ashes in the usual manner. The rotary feature can be applied to any baker's oven—as, for instance, to the 110 portable sheet-metal ovens. When the baking is completed, the main gates and the auxiliary gates and closing-blocks are opened by 115 raising their frame, so that access is given to the whole width of the baking-chamber. 115

In the Patent No. 591,224, granted to me on October 5, 1897, the arrangement of the auxiliary gates and the laterally-sliding blocks is shown. To this construction of auxiliary gates and laterally-shifting blocks I have added 120 the supporting-frame by which all the blocks can be raised simultaneously, which has been found to be an important improvement to the sliding blocks, as it permits the quick charging of an entire shelf and the quick removing 125 of the baked articles from the same whenever it should be necessary.

Instead of the fireplaces and heating-flues, which are attendant with much smoke and inconvenience, a heating obtained from the elec- 130

tric current can be used. The application of the same would be similar to that in electric cooking stoves, ranges, &c. The walls of the heating-chamber and the shelves would then 5 be suitably wired and connected with a source of electric power.

The advantages of my improved baking-oven are, first, that an enlarged floor or sole space is obtained, inasmuch as the three larger 10 shelves are equal in surface to one and one-half of the surface area of the ordinary oven, while the three smaller shelves are equal to three-fourths of the floor or sole surface of an ordinary oven. Consequently the six shelves 15 are equal to the floor-space of two and one-fourth ordinary ovens, while the improved oven takes up less depth in the bakeshop than the ovens heretofore in use. As one shelf is 20 filled after the other, the articles to be baked can be placed on the shelves quicker than when they are distributed over the deep sole-plate of the oven. Secondly, as soon as the shelves are 25 charged with the articles to be baked they are subjected to the high temperature of the upper part of the baking-chamber and then gradually passed into the lower part of the oven for final baking, by which the size and appearance of the articles are greatly improved. Thirdly, the 30 shelves can be charged either through a portion of the same, according to the articles to be baked. Fourthly, the baked articles can be quickly removed from the shelves as the same are turned in position on a level with the bottom of the main opening either through 35 the entire width of the same or by shifting and returning the closing-blocks, as desired. Fifthly, by the auxiliary gates and shifting blocks two men are able to work together in charging and discharging the bread, one working 40 at each side and charging the bread in a continuous straight line on his half of the shelf, while the other man attends to his half at the other end of the main opening, which permits the charging and discharging of each 45 shelf in a quicker manner than the charging process heretofore in use.

Having thus described my invention, I claim as new and desire to secure by Letters Patent—

1. In a baker's oven, the combination, with 50 a baking-chamber provided with a main opening, of rotatable frames in said opening, and baking-shelves pivotally supported by said frames of one length but alternately of larger

and smaller width, said shelves being so arranged that the wider shelves are pivoted 55 nearer to the center of the frames than the narrower shelves, substantially as set forth.

2. In a baker's oven, the combination, with a baking-chamber having a main opening, and a charging-board in front of the main opening having perforations, of a frame provided with guideways, a plurality of blocks movable in said guideways, means engaging the perforations of the board for shifting said blocks, and means for raising said frame together 65 with the blocks, substantially as set forth.

3. In a baker's oven, the combination, with a baking-chamber having a main opening extending across the full width of the chamber, of a frame, closing-blocks supported by said 70 frame, means for raising said frame together with the closing-blocks, means for shifting said blocks laterally, and a main gate for closing the main opening in front of said closing-blocks, substantially as set forth. 75

4. In a baker's oven, the combination, with a baking-chamber having a main opening, of a main gate for closing said opening, a second gate provided with two sets of guideways, auxiliary gates vertically movable in one set 80 of said guideways, shiftable closing-blocks laterally movable in the other set of guideways, means for raising said auxiliary gates independently of the second gate, and means for raising said second gate together with the 85 auxiliary gates and closing-blocks independently of the main gate, substantially as set forth.

5. In a baker's oven, the combination, with a baking-chamber having a main opening extending across the full width of said chamber, of shiftable closing-blocks in said main opening, a frame for supporting all of said closing-blocks, auxiliary gates movable in guideways of said frame at the corners of the same, and 95 a vertically-guided drop-gate for closing the main opening operated independently of said frame, substantially as set forth. 90

In testimony that I claim the foregoing as my invention I have signed my name in presence of two subscribing witnesses. 100
